JACKET OR SIMILAR ARTICLE

Emmette B. Massey, Charlotte, N. C.

Application July 2, 1954, Serial No. 31,260

Term of patent 3½ years

(Cl. D3—4)

The figure is a perspective view of a jacket showing my new design; the jacket front which is not shown is of conventional appearance and construction.

The essential feature of my design resides in the inflatable artificial wings shown in full lines on the drawing.

I claim:

The ornamental design for a jacket or similar article, substantially as shown and described.
